DESIGN FOR A SUIT

Bruno Staehle, New York, N. Y.

Application March 19, 1941, Serial No. 99,679

Term of patent 3½ years

To all whom it may concern:

Be it known that I, Bruno Staehle, citizen of the United States, residing at 25 Central Park West, New York city, in the county of New York and State of New York, have invented a new, original, and ornamental Design for a Suit, of which the following is a specification, reference being had to the accompanying drawing, forming part thereof.

I claim:

The ornamental design for a suit, substantially as shown.

BRUNO STAEHLE.
